UNITED STATES PATENT OFFICE.

CLARENCE N. FREY, OF CINCINNATI, OHIO.

METALLIC SHIPPING-CASE.

1,016,259.

Specification of Letters Patent.

Patented Feb. 6, 1912.

Application filed September 22, 1911. Serial No. 650,781.

To all whom it may concern:

Be it known that I, CLARENCE N. FREY, a citizen of the United States, residing at Cincinnati, in the county of Hamilton and State of Ohio, have invented certain new and useful Improvements in Metallic Shipping-Cases, of which the following is a specification.

My invention relates to metallic shipping cases, and has for its object the provision of a metallic shipping case of novel construction capable of being conveniently knocked down for shipment or storage and of being readily set up for use, and the invention will be readily understood from the following description and claims, and from the drawing, in which latter:

Figure 1 is a perspective view of my improved device in set-up relation. Fig. 2 is a horizontal cross-section of the same taken on the line 2—2 of Fig. 1, partly broken away. Fig. 3 is a vertical cross-section of the same taken on the line 3—3 of Fig. 1, partly broken away. Fig. 4 is a plan view 25 of the blank, partly broken away, from which the walls of the shipping case are formed. Fig. 5 is a plan view of the blank, partly broken away, from which the locking angular channeled corner-strip is 30 formed. Fig. 6 is a perspective view of the locking angular channeled corner-strip. Fig. 7 is a detail of a corner of one of the walls, with the flanges bent; and, Fig. 8 is a side elevation showing an enlarged detail 35 of one of the corners of the shipping case in set-up relation, showing the locking tongues in unlocked relation in dotted lines and in locked relation in full lines.

11, 11 represent the walls of the packing 40 case, which may include the sides, top and bottom of the case. These walls have edges of similar form and may be of sizes to conform to the size of the case desired. They are formed up from a metal blank, shown at 45 12, having end extensions 13. At the ends of the latter there are rabbets 14 for the purpose hereinafter described. The end extensions are bent back toward the body of the blank in the form of return-bend flanges 50 15 between which and the body channels 16 are formed. There is a recess 17 at each end of each flange.

18, 18, represent angular channeled corner-strips, and 19, 19, represent locking an-

gular channeled corner-strips. These corner-strips are metallic corner-strips formed up from blanks of metal. The blank from which the corner-strip 19 is formed up is shown at 20, in Fig. 5. It has a pair of tongues 21 at each end. The blanks from which the corner-strips 18 are formed up are similar to the blanks 20 without the tongues. The blank 20 has side-extensions 22 having rabbets 23 at the ends thereof, there being a slot 24 between the tongues 21 at each end of the blank. The side-extensions of the blanks for the corner-strips 18 and 19 are bent back toward the body of the blank for forming return-bend flanges 25 having channels 26 between them and the body of the blank. The corner strips are, provided with a longitudinal bend for forming wings 27 which project at right angles with relation to each other and form the corners 28, the strips being bent for causing the flanges at the respective sides thereof to approach each other.

In practice the angular channeled corner-strips 18 are of a length to correspond to the length of those edges of the walls of the case with which they coat, less the width of a pair of the wings 27, while the channeled portions of the locking corner-strips 19 are preferably of a similar length, these latter corner-strips having an addition thereto, however, the length of the locking tongues at each end thereof.

In setting up the shipping case, the sides of the case are preferably set up on edge, with the flanges on adjacent corners at 90 right angles to each other, the flanges at the respective corners being presented outwardly, the adjacent flanges of the sides being received in the channels of the corner-strips 18 at the respective corners of 95 the case, and vice versa, the flanges of the corner-strips 18 being received in the channels under the adjacent flanges of the sides. The bottom is preferably next put in place, the corner-strips 18 being similarly put in 100 place at two of the opposite edges of said bottom. All the corner-pieces 18 thus far assembled will have their ends located from the extreme corners of the packing case a distance corresponding to the width of one 105 of the wings 27, this positioning of the corner-pieces 18 connecting the sides, having enabled the two corner-pieces 18 connect-

ing the bottom to the sides to be slipped past the ends of the former, and in turn permitting two of the locking channelled corner-pieces 19 to be slipped past their 5 ends into connecting relation with the remaining flanges between the bottom and sides, the tongues projecting beyond the ends of the bottom, as shown in dotted lines in Fig. 8, the tongues being then bent 10 one across the other, as shown in full α lines in Fig. 8, outside the walls, and thereby locking the corner-strips 19 in place and preventing movement of any of the corner-strips 18 past the same. The tongues are 15 received in the recesses 17 at the ends of the wall-flanges for avoiding protrusion of the bent tongues and providing neat, strong and flush corners for the set-up shipping case. The top or cover of the case is now 20 ready to be put in place, which is done in manner similar to the assembling of the bottom on the sides.

In opening the shipping case it is only necessary to bend back the tongues at one 25 of the ends of each of the corner-strips 19 holding the top or cover in place, when these corner-strips and the corner-strips 18 connecting with the top or cover may be slipped endwise off the shipping case and the 30 top or cover removed. When the case is empty, it may be knocked down by removing the side corner-strips and disconnecting the bottom in manner similar to disconnecting the top.

35 My improved device forms a neat, strong and durable shipping case which is cheaply constructed and readily assembled in set-up relation or dismantled into knock-down relation.

40 Having thus fully described my inven-

tion, what I claim as new and desire to secure by Letters Patent, is:

1. A metallic shipping case comprising walls provided with return-bend flanges at the respective edges thereof which are 45 shorter than the edges on which they are located for forming recesses at the ends of said flanges, said flanges having flange-receiving channels thereunder, and corner-strips provided with mating return-bend flanges for said first-named flanges received under said first-named flanges through said recesses, said mating return-bend flanges having channels thereunder in which said first-named flanges are received. 50

2. A metallic shipping case comprising walls provided with return-bend flanges at the respective edges thereof which are shorter than the edges on which they are located for forming recesses at the ends of 60 said flanges, said flanges having flange-receiving channels thereunder, and corner-strips provided with mating return-bend flanges for said first-named flanges received under said first-named flanges through said 65 recesses, said mating return-bend flanges having channels thereunder in which said first-named flanges are received, and said corner-strips embracing locking corner-strips having end-tongues arranged for being bent into the longitudinal projections of other corner-strips. 70

In testimony whereof, I have signed my name hereto in the presence of two subscribing witnesses.

CLARENCE N. FREY.
